UNITED STATES PATENT OFFICE.

JOHN B. DENNIS, OF OTTUMWA, IOWA.

BANK-REGISTER.

SPECIFICATION forming part of Letters Patent No. 392,317, dated November 6, 1888.

Application filed February 21, 1888. Serial No. 264,764. (No model.)

To all whom it may concern:

Be it known that I, JOHN B. DENNIS, a citizen of the United States, residing at Ottumwa, county of Wapello, Iowa, have invented new and useful Improvements in Bank-Registers, 5 of which the following is a specification.

This invention relates to certain new and useful improvements in bank-registers; and it consists, substantially, in such features thereof as 10 will hereinafter be more particularly described.

In former Letters Patent granted me on the 27th day of December, 1887, No. 375,609, I have set forth certain improvements in this 15 class of inventions for the purpose of facilitating the rapid finding and checking off from the register the drafts bearing corresponding names and numbers; but I have found that while the invention covered by the Letters Patent aforesaid possesses many valuable features as compared with prior inventions on the 20 subject it is yet somewhat awkward, in first having to turn to a page by reference to a number at the sides for obtaining the thousands, and again turn a page by reference to a number 25 at the top to obtain the hundreds of the number sought; and the purpose of the present invention is to obviate the faults of the first invention by resorting to such devices as will hereinafter be more clearly set forth.

30 In the former Letters Patent referred to ten leaves are required for each thousand numbers, there being fifty numbers on a page, these leaves being cut in index form and having printed or stamped on the tabs formed by 35 such cutting the thousands of the numbers; also the individual leaves of each set of thousands are cut in like manner at the top or bottom, (preferably the top,) and have on the tabs thus formed the hundreds of the numbers. The 40 numerals constituting both the hundreds and thousands of the numbers are arranged on each opposite page at the top and sides, respectively, so as to enable a number to be found, whether the register be opened from the back 45 or front.

In the present invention, instead of cutting the leaves both at the sides and the top or bottom, (as may be preferred,) I cut each ten leaves (which represent a thousand numbers) 50 at the side edges to form tabs for the thousands of the numbers, and also at the sides I cut each individual leaf of the ten in successive

order, so as to form tabs for the numerals expressing the several hundreds. The cutting of each ten leaves is also necessarily greater or 55 less, accordingly as they may be cut from the top downward, or vice versa, so that the several thousands may be quickly read or referred to either front or back, as it will be understood may be done in this invention as well as 60 my former one, all as will more fully herein-after appear when taken in connection with the accompanying drawings, wherein—

Figure 1 is a view of my improved register, showing the same opened from one side; and 65 Fig. 2 is a similar view thereof as when opened from the opposite side.

In the drawings, A represents my improved register, the same being shown as beginning with 340,000 and ending with 344,999, as it is 70 to be understood that on each double page there is supposed to be a hundred numbers, (fifty on a page.) The numerals indicating the thousands are placed on the tab of the first page of the ten of a particular thousand in question, and the numerals expressing the quantity of hundreds of the numbers are placed numerically on the successively cut individual pages, this arrangement being had both at the top downwardly at the front of the register and from the bottom upwardly at the rear, 75 or vice versa, so as to enable a reading from either side. Suppose, for instance, that it is the wish to refer to number 342,320. All that is necessary to do is to simply open the register 80 at the place indicated by the thousands of the number 342, and then turn to the page indicated by the numeral 3, expressing the quantity of the hundreds of the number, and the 85 number will be quickly found, and which will 90 be a short distance down the left-hand page.

While I have herein shown and described the leaves of the register as being themselves cut, it will be understood that instead of this I may employ two sets of tabs (one for the 95 thousands and the other for the hundreds of the numbers,) without cutting the leaves, or I may resort to a combination of both tabs and cut leaves, the thousands appearing on the tabs and the hundreds on the leaves where cut. 100

Having thus described my invention, what I claim as new, and desire to secure by Letters Patent, is—

1. A bank-register containing a hundred

numbers on each double page, having each ten leaves cut at the sides in successive order, with numerals thereon indicating successively the thousands of the numbers, and also having the individual leaf of each set cut at the sides, and numerals thereon expressing successively the quantity of hundreds of the numbers, substantially as described.

2. A bank-register containing a hundred numbers on each double page, having each ten leaves cut at the side edges in successive order reversely at the front and back, with numerals thereon successively indicating the thousands

of the numbers, and also having the individual leaf of each set cut at the sides reversely in like manner, with numerals thereon indicating successively the quantity of hundreds of the numbers, substantially as described.

In testimony whereof I have hereunto set my hand in the presence of two subscribing witnesses.

JOHN B. DENNIS.
